United States Patent Office.

JOHN K. HARRIS, OF MADISON, INDIANA.

Letters Patent No. 62,132, dated February 12, 1867.

IMPROVEMENT IN APPARATUS FOR UNHITCHING HORSES FROM VEHICLES.

The Schedule referred to in these Letters Patent and making part of the same.

TO WHOM IT MAY CONCERN:

Be it known that I, JOHN K. HARRIS, of Madison, Jefferson county, Indiana, have invented a new and useful Unhitching Apparatus; and I hereby declare the following to be a full, clear, and exact description thereof, reference being had to the accompanying drawings making part of this specification.

My invention consists in a provision whereby a fractious or runaway horse may be instantly released by the driver.

Figure 1 is a perspective view, representing the front part of a carriage from which the horse has just been released.

Figure 2 represents the rear part of the shafts, together with the releasing strap and its accessories.

Figure 3 is an enlarged representation of the lock.

A represents the front portion of a carriage. The shafts B have a customary cross-bar, C, and are looped, D, to the front axle in the usual manner, but are entirely free from any whiffle-tree or other attachment for the customary tugs or traces, which I prefer to wholly dispense with, employing in their stead a tongue, E, projecting vertically upward from the harness at or about the intersection of the breast-collar strap F, (or the hame tug, where hames are used) and belly-band G. A spring, H, may be employed to compensate for the alternating side draught of the horse's shoulders. My releasable lock is constructed as follows: I is a box or frame fastened to the under side of the shaft, and having pivoted to it a vibratory hook, J, which, in conjunction with a stationary lip, K, affords a receptacle or socket, L, for the tongue. A spur, M, projecting rearward from the hook, is caught or detained by a sliding bolt, N, which bolt is held to its normal or effective position by a spring, O. A spring, P, serves to restore and hold the hook to lock at all times, save when yielding temporarily to the escaping tongue in the operation of release, as hereafter explained. The above-described details are of course duplicated on the other side of the horse. Extending rearward underneath the shaft, from the sliding bolt N, is a rod, Q, and from the corresponding bolt on the other side, a similar rod, Q'. These rods engage in arms R R', that depend from a bar, S, having another arm T for the attachment of a strap, U, which, passing rearward through an orifice either in the carriage floor or in the dash, terminates in a ring, V, convenient to the hand of the driver. The animal is very quickly hitched by the insertion of the tongue E behind the hook J, and may be completely and instantaneously released by a person within the carriage pulling the strap U sufficiently to draw back the bolt N clear of the spur M on the hook J, which then instantly yields to the forward stress of the tongue so as to release the latter and to set the horse at liberty, when the strap U becomes further useful by enabling the driver to hold up the shafts so as to prevent their entanglement with anything on the road. The carriage having come to rest the driver relaxes his pull on the strap, and thus permits the vibrating hook and the sliding bolts to spring back into lock.

I have selected for illustration the form preferred by me, but do not desire to restrict the invention thereto, as various modifications are possible; for example, a treadle or lever may replace the ring V and strap U, and the springs H and P may be omitted.

I claim herein as new and of my invention—

1. The provision, upon each shaft of a carriage, of a vibrating hook, J, adapted to receive and hold a tongue, E, upon the harness, and to be released by the driver, through the instrumentality of a strap, U, and its described or equivalent accessories, substantially as set forth.

2. The releasable hitching lock, consisting essentially of the vibrating hook J, sliding bolt N, and springs O and P, the same being placed under control of the driver by the strap U, and its accessories, as set forth.

In testimony of which invention I hereunto set my hand.

JOHN K. HARRIS.
